DESIGN FOR A COMBINED CLOCK AND KIDDIE SCHEDULE

Lola Cookston, St. Louis, Mo.

Application October 10, 1945, Serial No. 122,731

Term of patent 14 years

(Cl. D42—7)

To all whom it may concern:

Be it known that I, Lola Cookston, a citizen of the United States, residing at St. Louis, in the county of St. Louis and State of Missouri, have invented a new, original, and ornamental Design for a Combined Clock and Kiddie Schedule, of which the following is a specification, reference being had to the accompanying drawing, forming part thereof.

Fig. 1 is the front elevational view of a combined clock and kiddie schedule, showing my new design; and

Fig. 2 is the side elevational view of the same.

I claim:

The ornamental design for a combined clock and kiddie schedule, as shown.

LOLA COOKSTON.
